Ill., assignors to The Beardsley & Piper Company,
Chicago, Ill., a corporation of Illinois

Application November 15, 1937, Serial No. 174,633

16 Claims. (Cl. 22—36)

The invention relates to controlling-means for power-operated mechanism for moving sand-projectors over flasks.

In the use of sand-projectors which are movable over flasks of great area, the jointed structure comprising supporting-arms must be of great length, for ramming all portions of the flasks and this makes it difficult for an operator to manually move the projector and supporting-structure. A desideratum is to use projectors with sufficient capacity for throwing large quantities of sand which requires heavy projectors and supports. This heavy apparatus requires such great manual force in moving the projector over the flask that the operators can not endure the strain of the work.

One object of the invention is to provide manually-operable controlling-means for power-operated mechanism for shifting the jointed supporting-structure for the projector whereby the operator may easily control the horizontal movement of the projector in any direction over flasks of great area, responsively to manual movement of a control-device corresponding to the desired direction and extent of the projector.

Another object of the invention is to provide manual controlling-means which comprises a plurality of arms pivoted together and controlling-means for power-mechanism whereby a supporting structure comprising a pair of pivotally-supported arms, may be shifted correspondingly to the controller-arms, so that the operator can control the direction and extent of movement of the power-shifted supporting-arms by similar movements of the controller-arms.

Another object of the invention is to provide electrical control-means for power-operated mechanism for shifting the projector horizontally in any direction over flasks.

Other objects of the invention will appear from the detailed description.

The invention consists in the several novel features hereinafter set forth and more particularly defined by claims at the conclusion hereof.

In the drawings: Fig. 1 is a side elevation of a sandslinger embodying the invention, parts being shown in section. Fig. 2 is a diagram of the electrical apparatus and connections for controlling the movements of the supporting-arms by power. Fig. 3 is a vertical section of the manually-shiftable device for controlling the power-operated mechanism for shifting the supporting-arms. Fig. 4 is a longitudinal section through the pivotal supporting-connection between the stationary standard and the first horizontally-

swinging supporting-arm. Fig. 5 is a section of the pivotal supporting-connection between the pivotally-connected supporting-arms. Fig. 6 is a detail section on line 4—4 of Fig. 4 showing the cushioning device between the first supporting-arm and the power-driven mechanism for swinging it. Fig. 7 is a section on line 5—5 of Fig. 5 illustrating the cushioning device between the second supporting-arm and the power-operated shifting -mechanism for swinging it. 10

The invention is exemplified in apparatus for sling sand into flasks by means of a rotary projector which comprises a casing 10 and a rotary blade 11, which is fixed to, and driven at a high speed by, the shaft of an electric motor 12, which is supported so as to be horizontally movable with the projector. The projector is supported for universal horizontal movement over flasks to deliver wads of sand at high speed into all portions of large flasks by a jointed structure 20 which comprises a pair of arms A, B. Arm A is pivotally supported for horizontal movement on a stationary standard 14 and arm B is pivotally supported for horizontal movement on the distal end of arm A, so that either of the arms may 25 be moved to shift the projector, or their horizontal swinging movements may be compounded to bring the projector over all parts of the flask. Arm B is tubular and projector-casing 10 is fixed to the outer end of said arm. Electric motor 12, which drives the projector, is mounted adjacent the inner end of arm B. A sleeve 66, supported by roller-bearings 67 on stationary standard 14, is fixed to the inner end of arm A to support said arm for horizontal swinging 30

movement on said standard. Standard 14 is secured on the top of a stationary housing 13. The inner end of arm B has fixed thereto a bracket 73 which is fixed to the housing of motor 12. A spindle 72 is fixed to, and depends from, bracket 73, for pivotally connecting the inner end of arm B and the outer end of arm A for horizontal relative swinging movement of the arms. Spindle 72 is carried in a bracket or housing 92 which is fixed to the outer end of tubular 45 arm A.

The machine is equipped with means for feeding sand to the projector, such, for example, as a vibratory chute K, which contains a screen. Said chute is vibrated by an eccentric pin k^2 which is driven by reduction-gearing k . An electric motor k' drives gearing k . This gearing and motor are mounted on a bracket 97 which is fixed to the top of sleeve 66 so they will swing horizontally with arm A. One end of chute K is 50 55

supported by eccentric-pin k^2 , which is supported by the gearing k , and its other end is supported by a resilient strip k^3 . The chute, as thus supported, swings horizontally with supporting arm A. Chute K delivers the sand into a hopper I from which it falls onto an endless belt L, which is driven through suitable gearing (not shown) by motor 12, which drives the projector. This belt delivers the sand into the projector-casing. Hopper I and belt L are supported on, and to swing with, the supporting-arm B. This sand-feeding mechanism is adapted to continuously feed sand to the projector in all positions of the supporting-arms.

15 The invention provides for horizontally swinging supporting-arms A and B by power, in order to relieve the operator of the heavy work of moving the projector over the flasks and swinging the supporting-arms A, B. A reversible electric motor A' is provided for swinging the supporting-arm A in opposite directions around standard 14, and a reversible electric motor B' is provided for swinging supporting-arm B horizontally in opposite directions relatively to the supporting-arm A. Motor A' is connected to drive speed-reduction gearing 74, which is mounted in a housing 75, which is fixed to, and supported by, the stationary housing 13. Motor A' is supported from gear-housing 75. This gearing 74 drives a sprocket-wheel 71 to rotate arm A through a sprocket-chain 78 and a sprocket-wheel 79 which is connected by bolts 80 to the sleeve 66 which is fixed to arm A. For the purpose of cushioning the movements of arm A in its movement by power, the power from sprocket 79 is applied to arm A through a pair of rubber cushions 82. The inner ends of cushions 82 are provided with plates 83 for engaging the opposite sides of arm A and their outer ends are carried in a U-shaped bracket 84 which is fixed to, and rotates with power-driven sprocket-wheel 79. Bolts 80 pass through slots 81 in sprockets 79 to provide a loose connection between said sprocket and the sleeve 66 which is fixed to, and swings positively with, arm A, so that the initial swinging movement of the arm A, by power, will be cushioned. These cushions serve to avoid sudden jarring of the driving-mechanism in starting the movements of arm A and to prevent the momentum of the arm from racking the gearing at the conclusion of the swinging movements when the motor A' is stopped in controlling the movement of said arm A.

55 Motor B', which is provided for swinging arm B by power, is connected to swing said arm through speed-reduction gearing 85 in a casing 86 to which the casing of motor B' is secured. Casing 86 is fixed to bracket 92 which swings with arm A. Gearing 85 comprises a bevel-gear 87 fixed to a shaft 88 which is journaled in casing 86, a bevel-pinion 89, fixed to said shaft, and a bevel-gear 90 which is fixed to a sleeve 91 which is journaled in a bracket 92. Sleeve 91 is driven by power from motor B', to swing arm B through a forked bracket 93 which is fixed to the sleeve 91 and carries rubber cushions 94 with plates 95 for engaging arm B. This provides a cushioned driving-connection between sleeve 91 and arm B. Spindle 72 rotates in sleeve 91 so arm B will be shifted by said cushions 94.

70 The invention comprises a unitary manually-shiftable controlling-device for motors A', B', for swinging supporting-arms A, B to move the projector horizontally in any direction and varying distances over the flask. This controlling-device

comprises a controller-arm a which controls the operation of motor A' for swinging supporting-arm A and a controller-arm b which is pivoted to the distal end of controller-arm a and controls the swinging movement of supporting-arm B by motor B'. This controlling-device is manually shiftable by the operator to control mechanism which controls the operation of motors A', B' to move arms A, B, respectively, in direction and extent, to the movements of the controller-arms a , b . These controller-arms a , b are separately and simultaneously movable to cause separate or compound swinging movements of supporting-arms A, B and automatically control motors A', B' responsively to corresponding movements of the controller-arms.

This controlling-device and a seat M for the operator are preferably supported so they will move with the supporting-arm B which carries the projector. By mounting the operator's seat above the projector and on the supporting-arm B, he will be moved with the projector and can observe the delivery of the sand into all portions of the flask so that he can control the horizontal movement of the projector to uniformly ram all 25 portions of the flask with sand. Seat M is supported on a tubular bracket 101 which is fixed to supporting-arm B and a foot-rest 102 for the operator is fixed to said bracket. Controller-arm a is pivotally mounted to swing around a vertical 30 stud 103 which is fixedly supported in a bracket 100 which is clamped to bracket 101 in front of, and adjacent to, the operator's seat. Controller-arm b is pivoted on a stud 104 carried by the distal end of arm a and its handle b' is within 35 convenient reach of the operator.

The means for controlling the operation of reversible motor A' to swing supporting-arm A responsively to the movements of controller-arm a , comprises, an alternating current potentiometer which is mounted under controller-arm a and includes a laminated circular core composed of thin washers of transformer grade silicon steel, hereinafter referred to as a circular ring c with a toroidal winding and a rotatable contactor e 45 which is fixed to swing with said controller-arm a , and an alternating current potentiometer which is mounted in housing 13 and includes a stationary circular core with a toroidal winding, hereinafter referred to as ring C, and a contactor E which is rotatable directly with sprocket 79. Contactor E is fixedly secured to the lower end of a hollow shaft 96 which extends upwardly from housing 13 through standard 14 and is secured to rotate with sprocket 79 so that said contact-arm will rotate with supporting-arm A except for an occasional small angular displacement due to the compression of rubber cushions 82. One end of the winding of alternating current potentiometer ring C is connected by conductor c^3 60 to power-supply line-conductor 30, and its other end is connected by conductor c^4 to power-supply line-conductor 31. Likewise the corresponding ends of the winding on alternating current potentiometer-core c are connected to power-supply line-conductors 30 and 31 through conductors c' , c^2 , and conductors c^1 , c^1a , respectively. Alternating current potentiometer-rings C and c have their corresponding terminals connected across one phase of the power-supply line, and are energized at all times in equal phase and voltage in such manner that corresponding points on each of the two alternating current potentiometer-rings have exactly equal potentials.

75 Potentiometer-ring c of the controlling-device

is supported on a stud 103 above, and coaxially with, the axis of the pivotal connection between supporting-arms A, B and is bodily movable with, and rotatable relatively to, supporting-arm A. The same relative angular position of the stationary potentiometer-ring C in housing 13 and potentiometer-ring c of the manual controlling-device during the angular movements of supporting-arm A is maintained by a connection which comprises a sprocket-wheel 105, which is fixedly supported on a bracket 106 coaxially with the axis of standard 14, and arm A, and a sprocket-chain 107 which extends around fixed sprocket 105 and around a sprocket 108 to which is fixed the potentiometer-ring c under controller-arm a. This sprocket-wheel and chain connection, while supporting-arm A is shifted by power, maintains the same relative angular position between potentiometer-rings C, c in all angular positions of supporting-arm A. Contactor e is fixed to controller-arm a and rotates around ring c when said arm a is swung in either direction relatively to said ring c correspondingly to the direction and extent of movement of said arm a around stud 103.

The means for controlling the operation of motor A' includes an alternating current polar relay G which comprises a helix 63 around armature 62 and connected by conductor e' to contactors E, e, field-windings 60, 61, and a magnet m for holding the armature in its centralized position. Field-windings 61 and 60 are energized through conductors 37, 38, transformer windings J, J', and conductors e⁴, e⁵ from the same phase of power-supply as the windings of alternating current potentiometer-rings C, c.

Armature 62 is movable in opposite directions from its centralized position to shift either of a pair of switches 64, 65, which control a relay G, which controls circuits for operating motor A' in opposite directions. Switch 64, when armature 62 is shifted in one direction, closes against a contact 66 to establish a circuit through helix g⁴ for operating a switch g' which carries contacts 50, 51, 52 for closing a three-phase circuit through motor A' for operating the motor in one direction. Switch 65 is adapted to be closed at a contact 67, when armature 62 is shifted in the opposite direction, to control a circuit through winding g³ which operates a switch g² which carries contacts 53, 54, 55 for closing a three-phase circuit through motor A' for driving the motor in the reverse direction and correspondingly shifting the supporting-arm A. When arms a and A and, correspondingly, contacts e and E are in the same relative angular positions, no difference of potential will exist between contactors e and E, and no current will flow through the connecting circuit e, e¹, 63, e¹, 33, E. The pivoted armature 62 will then be equally attracted to each of the pole pieces energized by field-windings 61 and 60, so that armature 62 remains in its centered position by the attraction of permanent magnet m.

When controller-arm a is rotated clockwise in relation to ring c, contact e will vary its angular position relatively to contact E, so that a difference of potential will exist between these two points, causing current to flow through the circuit; contactor e, conductor e' and winding 63, lamp 33 and contactor E. Depending upon the relation of the phases between field-windings 60, 61 and armature-winding 63, armature 62 will be attracted by one pole-piece and repelled by the other, moving armature 62 to close switch 64 at 75. Current will now flow from the power-

supply conductor 30 through switch 66 and contact 64 through power-relay winding g⁴ to power-supply conductor 31, attracting armature g', closing main power-contacts 50, 51 and 52, and energizing motor A'. These connections are so related that motor A' is arranged to rotate arm A in such direction as to restore the equality of potential between contacts e and E. As soon as this equality of potential is established, winding 63 is no longer energized and centering-magnet m restores armature 62 to its center position to open switch 64 at contact 66, de-energizing power-relay winding g⁴, allowing armature g' to drop, and open contacts 50, 51 and 52 and stop motor A'.

When arm a is rotated in a counter-clockwise direction from a position in which arm a and arm A are in the same positions relatively to alternating current potentiometer-rings c and C, respectively, a difference of potential is again established between contacts e and E so that current will flow through the circuit including contactor e, conductor e' and winding 63, lamp 33 and contactor E. At this point the phase relation between the current flowing through armature-winding 63 and the current flowing through field-windings 60 and 61 is exactly opposite from the relation between these two currents which existed in the previous case in which arm a was rotated in a clockwise direction in relation to arm A, so that armature 62 will be attracted in the correct direction to close switch 65 at contact 67, thus permitting current to flow from the power-supply conductor 32 through switch 65, contact 67, conductor 39, and power-relay winding g³ to power supply conductor 31, attracting armature g², closing power-supply contacts 53, 54, 55, thus energizing motor A'. The closing of contacts 53, 54, 55 interchanges the connection of power-supply conductors 30 and 32 in relation to the connections which existed when contacts 50, 51 and 52 were closed, causing the motor to rotate in the opposite direction to rotate arm A in such direction as to restore the equality of potential between contacts e and E.

This exemplifies control-mechanism for the motor A' for swinging arm A responsively to the manual shift of the controller-arm a, whereby the supporting-arm will be shifted, in direction and extent, to correspond with the movement of said controller-arm by the operator. It also exemplifies mechanism controlled by said manually-shiftable controller-arm, in which a differential in voltage and reversal of polarity of current through a polar relay, are utilized to automatically control the swinging movements of the supporting-arm by the motor.

The vertical axis of stud 103 on which sprocket 108, ring c, and controller-arm a, are pivoted, is coaxial with the pivot between supporting-arms A and B, so that the control-device will move laterally with supporting-arm A and the axis of arm a of the control-device will remain coaxial with the pivot between the supporting-arms A, B during all of the swinging movements with the arm A.

The means controlled by the movements of controller-arm a for controlling the operations of reversible motor B' for swinging supporting-arm B, comprises an alternating current potentiometer which includes a laminated circular core composed of thin washers of transformer grade silicon steel with a toroidal winding, hereinafter referred to as a ring d, which is secured to rotate with controller-arm a and a contactor f, which is rotatable responsively to the pivotal

movements of arm *b* on its stud 104, and an alternating current potentiometer which includes a similar core wth a toroidal winding, hereinafter referred to as a ring *d*, which is fixed to bracket 92 on arm A and a rotatable contacter F, which is fixed to a shaft 99, which is secured to sleeve 91 so it will swing with sleeve 91 and arm B, except for slight angular displacement due to compression of rubber cushions 94. Ring *d* and contacter F are enclosed in a case 100 which is fixed to the bottom of bracket 92. Contacter *f* is secured to a sprocket-wheel 110, which is rotatable around the stud 103, and is rotatable by, and with, controller-arm *b*. Contacter *f* is rotated around ring *d*, responsively to the pivotal movement of controller-arm *b* relatively to controller-arm *b* by a sprocket 111 fixed to arm *b*, a sprocket-chain 112, and a sprocket-wheel 110, which is rotatable around stud 103, and carries contacters *f*. This connection causes the contacter *f* to rotate around ring *d* when controller-arm *b* is rotated on, and relatively to, controller-arm *a*, the effect being the same as if the ring *d* were fixed to the outer end of arm *a* and contacter *f* were fixed directly to arm *b*. The location of both of the rings *d*, *c* around stud 103, simplifies the electrical connections for said rings and the associated contacters. One end of the winding of potentiometer-ring D is connected by conductor *e*⁴ to power-supply line-conductor 30 and its other end is connected by conductor *e*⁵ to power-supply line conductor 31. Likewise, the corresponding ends of the winding on potentiometer-ring *d* are connected to power-supply line-conductors 30, 31 through conductors *d*', 30^a and *d*^a, 31^a respectively. Potentiometer-rings D, *d* have their corresponding terminals connected across one phase of the power-supply line and are energized at all times in equal phase and voltage in such manner that corresponding points on each of the two rings have exactly equal potentials.

The means for controlling the operations of motor B' includes an alternating current polar-relay H', which comprises a helix 70 around armature 71 and connected by conductors *f*' to contacters F, *f*, field-windings 68, 69 and a magnet *m*' for holding said armature in its centralized position. Field-windings 69, 70 are energized through conductors 31, 38, transformer-windings J, J', and conductors *e*⁴, *e*⁵, from the same phase of power-supply as the windings of potentiometer-rings D, *d*.

Armature 71 is movable in opposite directions from its centralized position to shift either of a pair of switches 72, 73 which control a relay G' which controls circuits for operating motor B' in opposite directions. Switch 72, when armature 71 is shifted in one direction, closes against a contact 74 to establish a circuit through helix *g*⁴ for operating its associated switch *g*', which carries contacts 56, 57, 58 for closing a three-phase circuit through motor B' for operating the motor in one direction. Switch 73 is adapted to be closed at contact 75 when armature 71 is shifted in the opposite direction to control a circuit through winding *g*³ which operates its associated switch *g*², which carries contacts 59, 60, 61 for closing a three-phase circuit through motor B' for driving the motor in the reverse direction and correspondingly shifting the supporting-arm A. When controller-arm *a* and supporting-arm A and, correspondingly, contacters *f*, F, are in the same relative angular position, no difference of potential will exist between said contacters and no current will flow through the

connecting circuit-contacter *f*, conductor *f*', and winding 70, lamp 33^f, and contacter F. The pivoted armature 71 will then be equally attracted to each of the pole-pieces energized by field-windings 68, 69, so that armature 71 remains in its center position by the attraction of permanent magnet *m*'. 5

When controller-arm *b* is rotated clockwise relatively to ring *d*, contacter *f* will vary its angular position relatively to contacter F, so that a difference of potential will exist between these two points, causing current to flow through contacter *f*, conductor *f*' and winding 70, lamp 33^f and contacter F, depending upon the relation of the phases between field-windings 68, 69, and armature-winding 70, armature 71 will be attracted by one pole-piece and repelled by the other, moving the armature to close switch 72 at contact 74. Current will now flow from the power-supply conductor 30 through conductor 30^a, contact 74, switch 72, conductor 41, winding *g*⁴ of relay G', conductor 35, ring D, and conductors *e*⁴, *c*³ and 30. This circuit will shift switch *g*' of relay G' and close main power-contacters 56, 57, 58 and energize motor B'. 20 These connections are so related that motor B' is arranged to rotate arm B in such direction as to restore the equality of potential between contacters *f*, F. As soon as this equality of potential is established, winding 70 is no longer 30 energized and centering magnet *m*' restores armature 71 to its center position to open switch 72 at contact 74 de-energizing said power-relay winding *g*⁴, allowing switch *g*' to drop and open contacts 56, 57, 58 and stop motor B'. 35

When arm *b* is rotated in a counter-clockwise direction from a position in which arm *b* and arm *a* are in the same positions relatively to potentiometer-rings *d*, D, respectively, a difference of potential is again established between 40 contacters *f*, F, so that current will flow through the circuit including contacter *f*, conductor *f*' and winding 70, lamp 33^f, and conductor F. At this point, the phase relation between the current flowing through armature-winding 70 and the current flowing through field-windings 69, 70, is exactly opposite from the relation between these two currents which was produced when arm *b* was rotated in a clockwise direction in relation to arm B, so that armature 71 will be attracted in the direction to close switch 73 at contact 75, thus permitting current to flow from the power-supply conductor 32 through switch 13, contact 75, conductor 42, power-relay winding *g*³ of relay G', attracting the armature-switch *g*² and closing power-supply contacts 59, 60, 61, thus energizing motor B'. The closing of contacts 59, 60, 61 interchanges the connection of power-supply conductors 30 and 32 in relation to the connections which existed when contacts 56, 57, 58 were closed, causing the motor to rotate in the opposite direction to rotate arm B in such direction as to restore the equality of potential between contacters *f*, F. 55

This exemplifies control mechanism for the motor B' for swinging arm B responsively to the manual shift of controller-arm *b*, whereupon the supporting-arm will be shifted, in direction and extent, to correspond with the movement of said controller-arm by the operator. 65

In moving the sandslinger to ram all portions of a flask, as desired, it is necessary to move the sandslinger horizontally varying distances in any direction, and back and forth, at the will of the operator and, for this purpose, it is nec- 70 75

essary to compound the pivotal movements of the supporting-arms. The controller-arms *a*, *b* are pivotally supported so they are simultaneously movable and so their movements may be compounded similarly to supporting-arms to control the power-driven mechanism for corresponding compound movements of the supporting-arms to reproduce either the simple or compounded movements of the controller-arms. The controller-arms are pivotally supported for angular movements corresponding to the angular movements of the supporting-arms. When both arms are shifted in the same, or in opposite, directions, the motors for shifting the supporting-arms, respectively, will be operated to effect movements of the respective supporting-arms in synchronism with, or responsive to, the direction and extent of the movements of the controlling-arms.

In operation, when the projector is to be shifted by the swinging of either or both of supporting-arms *A*, *B*, by power, the operator will move the handle *b'* of the controlling-device in whatever direction, and according to the extent he desires to move the projector and the movement of the controller-arms will, through the controlling mechanism, control the separate or simultaneous swinging movements of supporting-arm *A* by motor *A'* and the swinging of supporting-arm *B* by motor *B'* will be synchronized with, or in accordance with, the direction and extent of the movements of controller-arms *a*, *b* from handle *b'* by the operator. In other words, the operator merely moves either, or both, of the controller-arms through handle *b'* according to the direction and extent or path of movement desired of the projector and the controlling mechanism controls the operation of motors *A'*, *B'* to effect corresponding individual or simultaneous movements of supporting arms *A*, *B*. In practice, the movements of the supporting-arms are mostly always compounded to move the projector so it will traverse different paths and deliver sand into all portions of the flask, and these movements are readily controlled by correspondingly compounding the movements of the controller-arm. The movements of the handle *b'* in any direction or extent causes the power-shifted supporting-arms to follow the angular movements of the controller-arms.

The elements of the controlling mechanism are electrically connected, as indicated in Fig. 1. A series of conductor-rings 115 are connected to rotate with shaft 96, which rotates with supporting-arm *A*, and the conductors for current to electric motors 12, *K'*, *B'*, contact-arms *e*, *E*, *f*, *F*, and potentiometer-rings *D*, *c*, *d*, which are carried by the supporting-arms *A*, *B* are suitably connected to said conductor-rings. Shaft 96, which carries the contacter *E*, is fixed to an arm 79^a, which is fixed to sprocket-wheel 79, so said contacter will rotate with said sprocket, which operates supporting-arm *A* through cushions 82. Shaft 99, which carries contacter *F*, is secured to rotate with gear 90, which shifts supporting-arm *B* through cushions 94. By rotating these contacters with the driving gears 79, 90, respectively, they control the driving mechanisms to position the supporting-arms through the cushioned connections.

Field-windings 60, 61 of polar-relay *H* and field-windings 68, 69 of relay *H'* are connected to the secondary winding *J* of a transformer, to supply a reduced voltage to said windings. The primary coil *J'* of this transformer is connected

to conductors *e*⁴, *e*⁵, which are connected through conductors *c*³, *e*⁴ to line-wires 31, 32.

If either of the controller-arms *a*, *b* is quickly moved to a position considerably in advance of the corresponding positions of the supporting-arms *A*, *B*, respectively, an excessive potential difference will be established in the circuits between the contacters of the potentiometers. In order to avoid overloading and possible damage to the armature-windings 63, 70, a device having a positive coefficient of resistance versus temperature, for example, a tungsten filament lamp 33, is included in the line *e'* between contacters *e*, *E*, and a similar lamp 33^b is included in the line *f'*, between contacters *f*, *F*. During conditions of normal operation of the device, when only small differences of potential exist in the lines between the contacters, only small currents will flow through the positive resistance devices so that their resistance is maintained at a very low value and does not absorb any appreciable power from the circuit. As the potential between the connected contacters of the potentiometers is sharply increased, more current tends to flow through the positive resistance devices, causing their temperature to rise which, in turn, increases the resistance, thereby tending to offset, or maintain constant, the current flowing through the circuits.

Each of the motors *A'* and *B'* is usually provided with a magnetic brake (not shown), as well understood in the art, to release its rotor as soon as power is supplied to the motor-terminals and to engage a brake-drum on the rotor-shaft as soon as the current is interrupted to avoid the running of the motor on momentum after the current is turned off.

The invention exemplifies controlling-mechanism for power-operated mechanism for shifting a heavy projector for horizontal movement in any direction over a large flask *x*, by which the power-movements will be controlled by the operator from a single controlling-device which is movable correspondingly and proportionately to the desired movements of the projector. It also exemplifies controlling-means for the movement of a pair of supporting-arms which are pivotally supported for compound movements, which comprises controlling-arms which are adapted for similar movements. It also exemplifies electrical means for controlling power-driven mechanism for shifting the supporting-structure for a projector to move it over flasks of great area. It also exemplifies controlling-means which comprises a plurality of members swinging correspondingly to the swinging supporting-members of the sand-slinger, whereby the operator, by similar or corresponding movements of the control-members, will automatically control the power for moving the pivotally-connected supporting-members.

The invention is not to be understood as restricted to the details set forth, since these may be modified within the scope of the appended claims, without departing from the spirit and scope of the invention.

Having thus described the invention, what we claim as new and desire to secure by Letters Patent is:

1. The combination with a rotary projector for slinging sand, a pair of pivotally-connected arms for movably supporting the projector for horizontal movement in any direction, and means for feeding sand to the projector, of power-driven mechanism for swinging each of the pivoted supporting-arms, a manually-shiftable control-de-

- vice mounted on one of the supporting-members comprising a pair of correspondingly pivotally-connected members, one of which is mounted coaxially with the pivot between the supporting-arms, and means, controlled by the movements of said control-members, for controlling the operation of said mechanism to shift the projector, distantly and directionally, in response to the movements of the pivoted controlling-members.
2. The combination with a rotary projector for slinging sand, a pair of pivotally-connected arms for movably-supporting the projector for horizontal movement in any direction, and means for feeding sand to the projector, of electric motors for swinging the pivoted supporting-arms, a manually-shiftable control-device comprising a pair of correspondingly pivotally-connected members, one of which is mounted to swing coaxially with the pivot between the supporting-members, and electrical means, controlled by the movements of said control-members, for controlling the operation of the electric motors to shift the projector, distantly and directionally, according to the movements of the pivoted control-members.
3. The combination with a rotary projector and a pair of pivotally-connected arms for movably supporting the projector for horizontal movement in any direction, of reversible power-driven mechanism for respectively shifting the pivoted supporting-members, a manually-shiftable control-device comprising a pair of correspondingly pivotally-connected members, and means, controlled by the movements of said control-members, for controlling the operation of said mechanisms to shift the projector, distantly and directionally, in response to the movements of the pivoted controlling members, respectively, said means comprising a pair of potentiometers variable, respectively, by the movements of one of the supporting-members and one of the control-members, and a pair of potentiometers variable by the other supporting-member and controlling-member, respectively, and means controlled by the potentiometers for varying the direction in which the supporting-members are driven in response to the movements of the controller-arms, respectively.
4. The combination with a rotary projector and a pair of pivotally-connected arms for movably supporting the projector for horizontal movement in any direction, of reversible electric motors for respectively shifting the pivoted supporting-members, a manually-shiftable control-device comprising a pair of pivotally-connected members, and means, controlled by the movements of said control-members, for controlling the operation of said motors to shift the projector, distantly and directionally, in response to the movements of the pivoted controlling members, respectively, said means comprising a pair of potentiometers variable, respectively, by the movement of one of the supporting-members and one of the control-members, and a pair of potentiometers variable by the other supporting-member and controlling-member, respectively, and means controlled by the potentiometers for varying the direction in which the supporting-members are driven in response to the movements of the controller-arms, respectively.
5. The combination with a rotary projector and a structure for supporting the projector to move horizontally in any direction, of power-operated mechanism for shifting the structure, a manually-shiftable control-device, and electrical means controlled by movements of said device for

controlling the operation of said mechanism to shift the projector, distantly and directionally, in response to movements of the control-device, said means being controlled by variation of potential responsive to the movements of said device, and means for preventing overload of potential in the control-means when the control-device is shifted a considerable distance and the potential is greatly increased.

6. The combination with a rotary projector and a structure for supporting the projector to move horizontally in any direction, of power-operated mechanism for shifting the structure, a manually-shiftable control-device, and electrical means controlled by movements of said device for controlling the operation of said mechanism to shift the projector, distantly and directionally, in response to movements of the control-device, said means comprising a pair of potentiometers, controlled by variations of the potential responsive to the movements of said device, and means for preventing overload of potential in the control-means when the control-device is shifted a considerable extent and the potential is greatly increased.

7. The combination with a rotary projector and a structure for supporting the projector to move horizontally in any direction, of power mechanism for shifting the structure, cushioning-means between said mechanism and said structure, a manually-shiftable control-device, and means controlled by the movements of said device for controlling the operation of said mechanism to shift the projector, distantly and directionally, in response to the movements of the control-device.

8. The combination with a rotary projector and a structure comprising a pair of pivotally connected arms for supporting the projector to move horizontally in any direction, of power-mechanisms for shifting the arms, respectively, cushioning-means between said mechanisms and said arms, respectively, a manually-shiftable control-device, and means controlled by the movements of said device for controlling the operation of said mechanism to shift the projector, distantly and directionally, in response to the movements of the control-device.

9. The combination with a rotary power-driven projector, and a structure for supporting the projector to move horizontally in any direction so the projector will ram sand in all portions of a flask, of a manually and selectively operable control-device shiftable in accordance with the desired movement of the projector in all of the directions in which the projector is movable, and power-operated mechanism for shifting the structure to shift the projector, controlled by the selective movement of said device to operate said mechanism to shift the projector in direction and correspondingly to the selective movements of the control device.

10. The combination with a rotary power-driven projector, and a structure for supporting the projector to move horizontally in any direction so the projector will ram sand in all portions of a flask, of a manually and selectively operable control device shiftable in accordance with the desired movement of the projector in all of the directions in which the projector is movable, and power operated mechanism for shifting the structure to move the projector, controlled by the selective movement of said device to operate said mechanism to shift the projector in direction, correspondingly to, and a propor-

tionately greater distance than, the selective movements of the control device.

11. The combination with a rotary projector, a structure for supporting the projector to move horizontally in any direction so the projector will ram sand in all portions of a flask, and power-means supported by the structure for driving the projector, of power-operated mechanism for shifting the structure to move the projector horizontally in any direction, a manually and selectively shiftable control device operable in accordance with the desired movements of the projector in all of the directions in which the projector is movable, and means controlled by the selective movement of said device for controlling the operation of said mechanism to shift the projector in direction and correspondingly to the selective movements of the control device.

12. The combination with a rotary projector, a structure for supporting the projector to move horizontally in any direction so the projector will ram sand in all portions of a flask, and power means supported by the structure for driving the projector, of power-operated mechanism for shifting the structure to move the projector horizontally in any direction, a manually and selectively shiftable control device operable in accordance with the desired movements of the projector in all of the directions in which the projector is movable, and means controlled by the selective movement of said device for controlling the operation of said mechanism to shift the projector directionally and correspondingly to the selective movement of the control device, but over a greater range.

13. The combination with a rotary projector, a plurality of projector supporting members supported for separate or compound movement and power-means for driving the projector mounted on one of said members, of power-operated mechanism for shifting said members separately or simultaneously to move the projector horizontally in any direction to ram all portions of a mold, a manually and selectively shiftable control device operable correspondingly to the supporting members, and means controlled by the selective movement of the control device for controlling the operation of the shifting mechanism to pivotally move the supporting members singly or compoundly in extent and direction correspondingly to the selective movements of the control device.

14. The combination with a rotary projector, a plurality of projector supporting members pivotally supported for separate or compound movement and power-means for driving the pro-

jector mounted on one of said members, of power-operated mechanism for shifting said members separately or simultaneously to move the projector horizontally in any direction to ram all portions of a mold, a manually and selectively shiftable control device comprising a correspondingly plurality of members movable correspondingly to the supporting members, and means controlled by the selective movement of the control device for controlling the operation of the shifting mechanism to pivotally move the supporting members singly or compoundly in angular distance and direction corresponding to the selective movements of the members of the control device.

15. The combination with a rotary projector, a plurality of projector supporting members movably supported for separate or compound movement and power-means for driving the projector mounted on one of said members, of power-operated mechanism for shifting said members separately or simultaneously to move the projector horizontally in any direction to ram all portions of a mold, a manually and selectively shiftable control device comprising a corresponding plurality of members mounted for separate or compound movement correspondingly to the supporting members, and means controlled by the selective movement of the members of the control device for controlling the operation of the shifting mechanism to move the supporting members singly or compoundly in direction and extent correspondingly to the selective movements of the members of the control device.

16. The combination with a rotary projector, a plurality of projector supporting members pivotally supported for separate or compound movement and power-means for driving the projector mounted on one of said members, of power-operated mechanism for shifting said members separately or simultaneously to move the projector horizontally in any direction to ram all portions of a mold, a manually and selectively shiftable control device comprising a corresponding plurality of members pivoted for separate or compound movement corresponding to the movements of the supporting members, and means controlled by the selective movement of the members of the control device for controlling the operation of the shifting mechanism to pivotally move the supporting members singly or compoundly in angular extent and direction corresponding to the selective movements of the members of the control device.
